(57) **CLAIM**

The ornamental design for a lateral C-arm drape, as shown and described.

DESCRIPTION

FIG. 1 is a side perspective view of the first embodiment of a lateral C-arm drape in a raised position;

FIG. 2 is a side perspective view of the lateral C-arm drape of FIG. 1 in an expanded position;

FIG. 3 is a side, raised perspective view of the lateral C-arm drape of FIGS. 1 and 2 in a middle position between the collapsed position and the expanded position where the fasteners have been disengaged;

FIG. 4 is a front elevation view of the lateral C-arm drape of FIG. 3 in the middle position;

FIG. 5 is a rear elevation view of the lateral C-arm drape of FIGS. 3 and 4 in the middle position showing a fastener that can be used to attach the drape to the operating table or patient drape;

FIG. 6 is a right side elevation view of the lateral C-arm drape of FIGS. 3-5 in the middle position;

FIG. 7 is a left side elevation view of the lateral C-arm drape of FIGS. 3-6 in the middle position;

FIG. 8 is a top plan view of the lateral C-arm drape of FIGS. 3-7 in the middle position;

FIG. 9 is a top plan view of the lateral C-arm drape of FIGS. 3-8 in the middle position;

FIG. 10 is a side perspective view of the second embodiment of a lateral C-arm drape in a raised position;

FIG. 11 is a side perspective view of the lateral C-arm drape of FIG. 10 in an expanded position;

FIG. 12 is a side, raised perspective view of the lateral C-arm drape of FIGS. 10 and 11 in a middle position between the collapsed position and the expanded position where the fasteners have been disengaged;

FIG. 13 is a front elevation view of the lateral C-arm drape of FIG. 12 in the middle position;

(Continued)

FIG. 14 is a rear elevation view of the lateral C-arm drape of FIGS. 12 and 13 in the middle position showing a fastener that can be used to attach the drape to the operating table or patient drape;

FIG. 15 is a right side elevation view of the lateral C-arm drape of FIGS. 12-14 in the middle position;

FIG. 16 is a left side elevation view of the lateral C-arm drape of FIGS. 12-15 in the middle position;

FIG. 17 is a top plan view of the lateral C-arm drape of FIGS. 12-16 in the middle position; and,

FIG. 18 is a top plan view of the lateral C-arm drape of FIGS. 12-17 in the middle position.

The dash dot broken lines in the drawings depict environmental subject matter and form no part of the claimed design. The lighter dash lines depict portions of the Lateral C-Arm Drape that form no part of the claimed design. The bold dash lines depict fold lines that form no part of the claimed design.
